UNITED STATES PATENT OFFICE.

THOMAS J. FLAGG, OF NEW YORK, N. Y., ASSIGNOR TO FISK, CLARK & FLAGG, OF SAME PLACE.

DESIGN FOR A SCARF.

SPECIFICATION forming part of Design No. 15,294, dated August 19, 1884.

Application filed May 3, 1884. Term of patent 7 years.

To all whom it may concern:

Be it known that I, THOMAS J. FLAGG, of the city, county, and State of New York, have invented a new and original Design for a Scarf 5 for Men's Wear; and I do hereby declare that the following is a full and exact description thereof, reference being had to the accompanying drawing, and to the letters of reference marked thereon, making a part of this 10 specification.

My design involves the configuration of the outer apron, S, of the scarf as its prominent feature; and it consists, as represented in the drawing, of the two outwardly-bent centrally-curved unequal lateral lines, A B C D and A E 15 F G, forming an angle, A, at the top, and connected at the bottom by a line, G D. The two central re-entrant curves B C and E F in the lateral lines correspond in their degree of 20 curvature, but are of unequal length, and terminate in the straight or slightly-curved inwardly-inclined converging upper lines, E A and B A. The one curve, E F, is shorter than the opposite curve, B C, and the line E A 25 from the upper end of the curve F E is longer than the line B A, which extends from the curve C B, so that their point of intersection at A is on one side of an imaginary line, x x, drawn centrally through the length of the 30 scarf, and which is illustrated by dots in the drawing.

The form of the lower end of the scarf, between the points G and D, is not an essential feature of the design, and may therefore be 35 varied to represent either a straight, a curved, or a broken or angular line.

The design is completed by a prolongation

of the shorter curve F E beyond the point F until its length corresponds to that of the opposite curve, B C, and from its upper end at 40 H a straight line, H I, of the same length of the opposite line, B A, extends upward at an inward angle of inclination corresponding to that of said line B A, and the ends of these two converging lines B A and H I are connected 45 by a top line, A I, which completes the outline of the entire scarf. A line, I K, extends inwardly from the upper angle, I, to intersect the line A E at the point K, where it is intersected by the central imaginary line, x x, and, 50 in combination with the lines E H I, I A, and A E, serves to define the edges or outlines of the inner apron, T, and center piece, U, of the scarf.

I claim—

The design of a made-up scarf, herein shown and described, which consists of the unequal lateral lines and angles A B C D, A E F G, which, in connection with a straight, curved, or angular line or edge between the points C 60 and D, define the outline of the outer apron of the scarf and of the upper outer line, E H I, top line, I A, and inner line, I K, which define the inner apron, T, and center piece, U, and complete the configuration of the entire 65 scarf.

In testimony whereof I have signed my name to this specification in the presence of two subscribing witnesses:

THOMAS J. FLAGG.
